ROAD MACHINE

James B. Jarmin, Dallas, Tex., assignor, by mesne assignments, to Allis-Chalmers Manufacturing Company, Milwaukee, Wis., a corporation of Delaware

Application December 21, 1936, Serial No. 116,873

3 Claims. (Cl. 37—155)

This invention relates to new and useful improvements in road machines.

One object of the invention is to provide a road machine frame wherein an improved single longitudinal connecting member is utilized for connecting the front and rear ground wheels of said machine.

An important object of the invention is to provide an improved road machine having a longitudinal connecting member constructed of an H-beam or I-beam, whereby the member may be constructed of one piece and bent to any desired shape which eliminates elbows, or other connections, and adds to the rigidity or stability of the machine.

Another object of the invention is to provide an improved road machine including a longitudinal reach member which is secured at one end to the rear platform of the machine in such a way that the longitudinal axis of the reach member is at all times, at a right angle to the longitudinal axis of the rear axle of the machine, whereby danger of twisting strains or side thrust, due to the machine operating on a grade or incline, impairing the efficiency of the machine is eliminated.

Still another object of the invention is to provide an improved means for securely fastening the end of a longitudinal reach member to the rear platform of a road machine, whereby the structure is strengthened and the reach member firmly held in proper position.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a side elevation of a road machine, constructed in accordance with the invention,

Figure 2 is a partial plan view,

Figure 3 is an enlarged side elevation of the rear end of the reach member and showing its connection to the rear platform,

Figure 4 is an enlarged longitudinal sectional view of the parts shown in Figure 3, and taken on the line 4—4 of Figure 2, and

Figure 5 is an enlarged, transverse, vertical, sectional view, taken on the line 5—5 of Figure 1.

Figure 6 is a perspective view of the rear platform.

In the drawings, the numeral 10 designates a flanged reach member which forms the main

support of the road machine frame. This member may be an I-beam or an H-beam but is preferably the latter because an H-beam is provided with wider flanges more suitable for this particular member. The reach member may 5 include a substantially horizontal section A and a forwardly inclined section B which is bent therefrom. The forward end of the inclined section B is supported on the front running gear 11 of the road machine in any suitable manner, 10 as is now common in this art. A sub-frame 12 has its forward end pivoted to the running gear 11, while its rear end is suspended by a hanger 13 as is the common practice. The upper end of the hanger 13 is pivoted to an arm 11', which 15 is hinged on a bracket 12' extending outwardly from a collar 13' which is clamped, bolted or otherwise secured to the member 10. A suitable scraper blade 14 is carried by the sub-frame being mounted thereon in any suitable way. 20

The rear end of the reach member or beam 10 is bent upon itself so as to incline downwardly as shown at 15 and a base plate 16 having a substantially rectangular shape is welded to this end of the beam. The plate 16 extends in 25 a substantially horizontal plane. It is noted that by constructing the member 10 of an I-beam or an H-beam, it is possible to bend said member upon itself and thus eliminate the use of elbows or other connections for making the 30 comparatively sharp turn between the horizontal portion A and the inclined portion 15 of said member. If desired, the beam 10 may be strengthened and braced by side plates 17 which extend from the rear end of the forwardly inclined portion B to the base flange 16, one of the plates being secured on each side of the beam between the outwardly directed flanges thereof. The plates are secured to said flanges by welding or other means. 40

The base plate 16 is larger than the end of the reach member or beam 10 so that a peripheral flange 16' is formed around the end of said member. The base plate 16 sets within a recess 18 formed in the top of the rear platform 19 of the 45 machine. The recess 18 extends longitudinally of the platform, whereby when the plate 16 is disposed therein, lateral displacement of said plate is prevented. Bolts 20 pass through the base plate 16 and through the top of the platform 50 19 and receive nuts 21, whereby the base plate is securely fastened to the platform which rigidly fastens the rear end of the beam 10 to said platform. To further secure the rear end of the reach member or beam 10 to the platform, said platform 55

is provided with a forwardly directed, flanged extension 22. A vertical channel member 23 has its lower end secured to the forward end of the extension 22, with the flanges 23' of said member 5 overlying the sides of the extension and being welded thereto. The upper end of the channel member is formed with a cut-out or recess 24 which receives the beam 10, whereby the extreme upper end of the member 23 extends contiguous 10 to the reinforcing side plate 17. This end of the member 23 is welded, or otherwise suitably fastened to the side plate 17 and it will be obvious that with this structure a rigid brace is provided for more firmly fastening the rear end of the 15 reach or beam 10 to the platform 19.

The sides and rear of the platform 19 are formed with an integral depending apron 25, the lower end of which rests on horizontally extending angle bars 26. An outwardly extending flange 20 25' is formed at the lower end of the apron 25 and bolts 27 pass through this flange and through the angle bars 26 and receive nuts 28 on their lower ends, whereby the platform is securely fastened to the angle bars. The transversely extending rear axle 29 is supported on the angle bars 26. The axle is preferably substantially square in cross-section and is provided with horizontally directed, longitudinal flanges 29' on each side thereof. The flanges, of course, rest upon 30 the upper end of the angle bars and straps 30 and retaining angles 31 (Figure 3) have their ends overlying the flanges 29' and are bolted to the supporting angle bars 26, whereby the axle is secured on said bars. The outer ends of the 35 axle 29 have the usual rear ground wheels 32 secured thereto and with such structure, it will be obvious that the wheels support the rear platform 19 and also the rear end of the reach member or beam 10.

It is noted that the recess 18 which extends 40 longitudinally in the top of the platform 19 is disposed at substantially a right angle to the longitudinal axis of the axle 29. Therefore, when the rear end of the beam 10 is secured within this recess, said beam has its longitudinal 45 axis at substantially a right angle to the rear axle 29. Since the base plate 16 is resting within the recess 18, it will be seen that the rear end of the beam is held in its proper position at all 50 times and any twisting strains or sidethrusts which may occur due to the rear ground wheels 32 riding on an incline or grade, cannot cause the beam 10 to move out of its proper position. In other words, the positioning of the base plate 55 16 which is welded or otherwise secured to the beam 10, within the recess 18 provides a positive means for holding this rear end of the beam in a fixed position on the platform 19.

As before stated, it is preferable to construct 60 the reach member 10 of an H-beam because of the increased width of the flanges of said beam. However, an I-beam having smaller flanges, could be employed. In either case, the beam may be

readily bent to conform to any desired shape and thus, it is possible to construct the reach member of a single piece without the use of any elbows or other connection in order to make the necessary turns or curves in said member. Obviously, by making the reach member of a single beam or section, the strength of the frame is greatly increased. Also the manufacturing is made easier and the cost reduced. It is pointed out that an H-beam or an I-beam has been 5 found particularly adaptable because the same gives the necessary strength and rigidity to the frame without obstructing the operator's view of the blade 14. It is pointed out that although the side plates 17 have been shown to reinforce 10 the rear portion of the beam 10, these side plates could, if desired, be eliminated and a suitable frame constructed without the use of these plates. 15

What I claim and desire to secure by Letters Patent is:

1. A road machine including, a front wheel assembly, a rear wheel assembly including a platform with a longitudinal recess formed in its top, a longitudinal reach member formed with flanges on its longitudinal sides pivotally secured 20 to the front wheel assembly, a base plate secured to the rear end of said reach member and forming a peripheral flange therearound, means to fasten said peripheral flange in said recess of 25 said platform, and a working tool suspended from said reach member between the wheel assemblies 30 thereof.

2. In a road machine, a longitudinal reach member having a downwardly inclined portion at its rear end, a front support for said reach member, a rear support for said reach member including an axle, relatively abutting members associated respectively with said inclined portion of said reach member and with said axle, one of said relatively abutting members being a plate 40 element and the other having a recess into which said plate element is fitted to prevent relative displacement of said reach member and axle 45 longitudinally of said axle, and means retaining said plate member in said recess.

3. In a road machine, a longitudinal reach member having a downwardly inclined portion at its rear end, a front support for said reach member, a rear support for said reach member including an axle, and connecting means between 50 said inclined portion of said reach member and said axle adapted to prevent axial and horizontal angular displacement of said axle relative to said reach member, said connecting means including relatively abutting members associated 55 respectively with said reach member and axle, one of said abutting members having a plane surface and marginal portions rising therefrom, and the other abutting member contacting said plane surface and being fitted between said marginal portions, and means retaining said abutting members upon each other.

JAMES B. JARMIN.
